UNITED STATES PATENT OFFICE.

FRANK E. MILLER, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

DOOR-SUPPORTING MECHANISM.

Application filed April 17, 1923. Serial No. 632,632.

To all whom it may concern:

Be it known that I, FRANK E. MILLER, a citizen of the United States, residing in Pittsburgh, in the county of Allegheny and 5 State of Pennsylvania, have invented certain new and useful Improvements in Door-Supporting Mechanism, of which the following is a specification.

This invention relates to means for supporting the discharge doors of a railway car or the like and has for an object the provision of a plurality of movable members which will cooperate with a discharge door to hold it in closed or partly closed positions.

Another object of the invention is to provide a railway car or the like with a plurality of door supporting means so associated with each other that they are movable 20 simultaneously out of door supporting positions and movable relative to each other to door supporting positions.

A further object of the invention is to provide a railway car or the like with a pair of discharge door supporting members each having a door supporting ledge in a different plane from the other, whereby said discharge door may be supported in closed or partly closed position.

These and other objects will be apparent from the following description.

Referring to the drawings in which like reference characters refer to like parts, Fig. 1 is a plan view of a portion of a railway dump car embodying the invention; Fig. 2 is a side elevational view of the same, Fig. 3 is a like view showing the operation of the invention when the discharge door is being moved toward closed position; Fig. 4 is a 40 sectional view taken on the line 4—4 of Fig. 2; Fig. 5 is a sectional view of the door supporting members taken on the line 5—5 of Fig. 2; Figs. 6 and 7 are views like Figs. 2 and 3, illustrating a modification of the invention.

Referring now in detail to the drawings, the reference character 1 indicates the car body which may be of any suitable construction and which for illustrative purposes 50 comprises a floor 2, discharge doors 3 and side walls 4, all of which may be of any preferred construction.

Each of the discharge doors 3 is preferably provided with members 5 the outer

ends of which preferably extend outwardly 55 to a point beyond the outside plane of the side wall and each is adapted to be engaged by door supporting members 6 and 7 which are pivotally mounted on a bolt 8 mounted in a bracket 9 secured to the side wall 4. 60 The members 6 and 7 are provided with ledges 10 and 11 respectively, which are adapted to engage the lower surfaces of the members 5 to support the door. These ledges 10 and 11 are arranged in different 65 horizontal planes, the ledge 10 being in a plane below that of the ledge 11 so that as the door is being closed the member 6 will move relatively to the member 7 to such a position that the ledge 10 will be adapted to 70 support the door in partly closed position. When the door is in closed position the member 7 will move relative to the member 6 to such a position that the ledge 11 will 75 engage the underside of the member 5 and will thus support the door in closed position. The front edge portion of each of the members 6 is provided with a laterally extending lug 12 which is adapted to engage the front edge portion 13 of the member 80 7 when the discharge door is in closed position and when the members 6 and 7 are being moved in the direction as indicated by the arrows in Fig. 2 to open the door. This lug is so arranged that it will engage the 85 member 7 when the member 6 is moved toward door releasing position and will thus insure at all times the simultaneous movement of both of the members in this direction and will permit relative movement between these members in the opposite direction.

The lower portions of the members 6 and 7 are provided with sloping surfaces 14 with which the member 5 on the door will engage 90 when the door is being closed and which when in such engagement will cause the members 6 and 7 to move out of the path of the members 5 to permit the door to be moved to closed or partly closed position.

Assuming the discharge door 3 to be in closed position and it is desired to open it, the operator strikes the front edge of member 6 or lug 12 a blow with a sledge or other tool which causes the members 6 and 7 to 100 move simultaneously in the direction as indicated by the arrows in Fig. 2 out of door supporting positions at which time the door

will move to its open position and the members 6 and 7 will return by gravity to their door supporting positions.

When it is desired to close the doors, the operator by the use of a bar or other suitable device, raises the door and as this is done and the member 5 secured to the door comes into engagement with the sloping surfaces 14 of the members 6 and 7 these members will be caused to move simultaneously out of the path of the member 5 until such time as the lower surface of this member is raised to a position above the supporting ledge 10 of the member 6 at which time the member 6 will move independently of the member 7 in a direction toward the member 5 a sufficient distance so that the ledge 10 will be under the member 5. If the operator desires he may now permit the member 5 to rest on the ledge 10 to support the door in partly closed position. When the member 6 is supporting the door in partly closed position it will be noted from Fig. 2 of the drawings that the member 7 is held out of its door supporting position by its engagement with the side of the member 5. To finally close the door the operator continues to raise the door until it is in its closed position at which time the member 7 will move to such a position that the ledge 11 will engage the underside of the member 5 and when in this position will support the door in closed position. The operator now moves the cam members 15 into engagement with the members 6 and 7 thus locking these members against accidental movement.

In Figs. 5 and 6 a modification of the invention has been illustrated in which the door supporting member 6 is pivotally connected with the door supporting member 7 at a point remote from the point where the member 7 is pivotally connected with the car. The operation of these members 6 and 7 are substantially the same as the members 6 and 7 hereinbefore described in connection with the preferred form of the invention.

It will be apparent to those skilled in the art to which this invention appertains that changes may be made in the details and arrangement of parts forming the invention without departing from the spirit and scope of the appended claims.

Claims:

Having thus described the invention, what I claim as new and desire to secure by Letters Patent is:—

1. In a dump car, a discharge door, a member pivotally mounted on said car for supporting said door in closed position, a member movably mounted on the first mentioned member for supporting said door in partly closed position, and means whereby both of said members are simultaneously movable out of their door supporting positions.

2. In a dump car, a discharge door, a pivotally mounted member for supporting said door in closed position, a pivotally mounted member for supporting said door in partly closed position, and means on the front edge of one of said members adapted to engage the front edge of the other of said members to effect the simultaneous movement of both of said members out of their door supporting positions. 70 75

3. In a dump car, a discharge door, a pivotally mounted member for supporting said door in closed position, a pivotally mounted member for supporting said door in partly closed position, and a lug on the last mentioned member adapted to engage the front edge of the first mentioned member whereby both of said members are caused to move simultaneously out of their door supporting positions. 80 85

4. In a dump car, a discharge door, a member for supporting said door in closed position, a member pivotally mounted on the first mentioned member for supporting said door in partly closed position, both of said members being adapted to be in their door supporting positions when the door is open or closed, means whereby both of said members are simultaneously movable out of their door supporting positions as the door is being operated and means whereby one of said members is permitted to move into door supporting position in advance of the other of said members to support said door in partly closed position. 90 95 100

5. In a dump car, a discharge door, a member pivotally mounted on said car having a ledge adapted to support said door in closed position, a member pivotally mounted on the first mentioned member having a ledge formed thereon adapted to support said door in partly closed position, and means whereby one of said ledges is held out of its door supporting position when the other of said ledges is in its door supporting position. 105 110

6. In a dump car, a discharge door, a member connected with said door and projecting beyond the free edge thereof, a plurality of members having ledges arranged in different horizontal planes adapted to engage the projecting portion of said member to successively support said door in partly closed and closed position, one of said members being pivotally mounted on another of said members. 115 120

7. In a dump car, a discharge door, a projection on said door, a member adapted to support said door in partly closed position, a member adapted to support said door in closed position, both of said members being normally in the path of said projection, means at the front edge of both members whereby said members are movable simultaneously and automatically out of the path 125 130

of said member as the door is being closed, and means whereby said members engage said projection one at a time as the door is being closed.

- 5 8. In a dump car, a discharge door, a member depending from said car and supporting said door in closed position, a member pivotally mounted on the first mentioned member adapted to support said door in partly closed position and means on one of said members adapted to engage the other of said members to insure the simultaneous movement of both of said members toward their door releasing positions.
- 10 9. In a dump car, a discharge door, a plurality of members for supporting said door, one of said members being mounted on said car and adapted to support said door in partly closed position and the other being mounted on the first mentioned member adapted to support the door in closed position, and means whereby the last mentioned member is held out of its door supporting position until said door is closed.
- 15 10. In a dump car, a discharge door, a member pivotally mounted on said car, for supporting said door in closed position, and a member pivotally mounted on the first mentioned member for supporting said door in partly closed position.
- 20 11. In a dump car, a discharge door, a member pivotally mounted on said car for supporting said door in closed position, and a member pivotally mounted on the first

mentioned member for supporting said door in partly closed position, the pivot point of the last mentioned member being spaced away from the pivot point of the first mentioned member.

- 25 12. In a dump car, a discharge door, a member mounted on said car for supporting said door in closed position, a member mounted on the first mentioned member for supporting said door in partly closed position, and means whereby said members are simultaneously movable out of door supporting positions.

13. In a dump car, a discharge door, and a plurality of members for supporting said door in different positions, one of said members being pivotally mounted on said car and another of said members being pivotally mounted on the first mentioned member.

- 30 14. In a dump car, a discharge door, and a plurality of members for supporting said door in different positions, and means on one of said members adapted to engage the front edge of another of said members whereby said members are simultaneously movable out of their door supporting positions.

In testimony whereof I affix my signature in the presence of two witnesses.

FRANK E. MILLER.
